US00D847841S

(12) **United States Design Patent** (10) Patent No.: **US D847,841 S**
Baker et al. (45) Date of Patent: ** May 7, 2019

(54) **DISPLAY SCREEN OR PORTION THEREOF WITH GRAPHICAL USER INTERFACE**

(71) Applicant: **Apple Inc.**, Cupertino, CA (US)

(72) Inventors: **Robert W. Baker**, Cupertino, CA (US);
Sebastian Boltz, Elmshorn (DE);
Joshua W. Decker, San Francisco, CA (US); **Ole Lagemann**, Rellingen (DE)

(73) Assignee: **Apple Inc.**, Cupertino, CA (US)

(**) Term: **15 Years**

(21) Appl. No.: **29/624,545**

(22) Filed: **Nov. 1, 2017**

(51) LOC (11) Cl. **14-04**

(52) U.S. Cl.

USPC **D14/486**

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines illustrate a display screen or portion thereof, and form no part of the claimed design.

1 Claim, 1 Drawing Sheet
(1 of 1 Drawing Sheet(s) Filed in Color)
